SHOEMAKING

William M. Page, Marblehead, Mass.

Application May 22, 1936, Serial No. 81,221

4 Claims. (Cl. 12—146)

This invention relates to the manufacture of shoes. It consists in an improved process of making flexible, single sole shoes of superior quality from the shoe-making standpoint to those heretofore known and is characterized by certain advantages in economy as well as ease and efficiency in practice. The invention is of general application to the broad field of shoemaking, although it has a particular field of use in the manufacture of slippers, and for illustrative purposes it will be disclosed in detail in that application.

The invention consists in a novel process of forming the counter portions of shoes without a back seam. In the type of shoe herein selected for purposes of illustration, the counter portion comprises a heel pocket which may be given its finished shape independently of the forepart of the upper, either by molding upon the heel end of a last or upon a suitably shaped mold. As herein shown the heel pocket comprises an outer seamless portion and a lining portion and these are united in superposed relation and are adapted to receive in interleaved relation a blank of stiffening material capable of being temporarily softened and of being then transformed into a stiff resilient condition by drying or cooling. The present invention contemplates the insertion of such a stiffening blank into a heel pocket or counter portion of a shoe, the molding or shaping of the entire margin of the assembled heel pocket upon a last or form, as by a heel seat lasting operation or its equivalent, and then the drying of the molded parts thus converting them permanently into a stiff resilient shape conforming accurately to the fine lines of the last which are desired in the finished shoe.

A characteristic of a heel pocket or counter portion manufactured in accordance with the present invention preferably is that the line of juncture between the lining and the outer part is brought inside the heel pocket, that is, the fold vertex is formed entirely in the outer portion thereof, and that the upper edge of the stiffening blank extends above this line of juncture, or fully into the fold vertex. By this procedure an attractive rolled edge effect is imparted to the heel pocket and its entire body is maintained reliably in the molded shape imparted to it.

These and other features and characteristics of the invention will be best understood and appreciated from the following description of a preferred manner in which it may be carried out, selected for purposes of illustration and shown in the accompanying drawing in which—

Fig. 1 is a plan view of a heel pocket, stitched and in flat condition before it is turned.

Fig. 2 is a plan view of the counter stiffening blank.

Fig. 3 is a fragmentary view showing the heel pocket with the stiffening blank assembled therein.

Fig. 4 is a view in cross section of the assembled heel pocket on the line 4—4 of Fig. 3.

Fig. 5 is a view in perspective, illustrative of 10 the heel seat lasting step.

Fig. 6 is a view in perspective, showing the lasted heel pocket in position upon a lasted shoe, and

Fig. 7 is a view in side elevation of the completed shoe.

The heel pocket is prepared by first stitching together a lining blank 10 and a leather or outer blank 11 while the two blanks are superposed, inside out, in flat condition. Both the blanks 10 and 11 are integral seamless pieces, complete in themselves and having no back seam. The line of marginal stitching 12 extends about the upper and side edges of the blank which, as shown, are cut in a continuous curved contour. The heel pocket in this early stage of its preparation is shown in Fig. 1, and it will be understood that both the lining and outer blanks are now inside out. The stitched heel pocket is now turned right side out, bringing the lining 10 to the inside and concealing the stitch line by the rolled edge of the leather or outer blank, that is to say, the fold vertex is formed entirely in the material of the outer blank 11 and the line of juncture is brought down below the upper rolled edge.

The next step of the process is to prepare a stiffening blank 13 from material which may be temporarily mulled or softened as will presently be explained. For this purpose a celanese textile fabric impregnated with a pyroxylin compound may be employed, and this may be softened by a suitable organic solvent, or "cold water box" material which is capable of being softened by water may be employed. Thermoplastic sheet material is also suitable for purposes of the present invention. A blank of some such material is shown in Fig. 2 of the drawing. It is assembled in the heel pocket by being slipped between the outer and lining portions so that its upper edge is carried clear to the fold vertex, that is to say, the stiffening blank extends continuously past the line of juncture between the lining and the outer portion of the heel pocket as best shown in Fig. 4. The stiffening blank 13 may, if desired, be secured in this position by a band of cement 14, previously

5 applied to the upper margin of the outer blank 11 as suggested in Fig. 3, but under many circumstances it is not necessary so to cement the stiffening blank, since the operation of assembling the heel pocket upon the last has the effect of 10 securely anchoring the stiffening blank in place.

10 Having prepared the heel pocket and provided it with its interleaved stiffening blank, the lasting operation may now be carried out. For this purpose the heel pocket is temporarily opened and softening liquid applied to the stiffening blank or, if a thermoplastic material is used, the stiffening blank is heated to a softened condition. Whatever softening step may be employed, the 15 assembled heel pocket is next positioned upon the heel end of the last 14 and secured symmetrically thereon by means of a single tack 15, driven into the heel end of the last. The forepart of the upper, together with the shank piece 20, has already been applied to the last and the margin of 20 the heel pocket extends upwardly about the rear end of the last and shank piece.

25 The next step in the manufacture of the shoe consists in drawing the forward ends of the heel pocket inwardly by hand over the last bottom and securing them in place by tacks 17. In the same way the rear end of the upstanding margin is pulled inwardly and secured by a single tack 18. It will be understood that the material of 30 the stiffener is soft and pliable during these steps and offers no resistance to the overworking of the margin of the pocket.

35 Having prepared the shoe as indicated in Fig. 5, it is presented to a heel seat lasting machine, the wipers of which are represented in Fig. 5. When the shoe has been properly located in the heel band of this machine the wipers are advanced simultaneously, the entire upstanding margin of the heel pocket is wiped into place and while so held under pressure the heel seat lasting tacks 19 are simultaneously driven, thus conforming the heel pocket accurately and tightly to the heel end of the last and in this process molding the 40 stiffening material into the desired shape. In 45 the step of subjecting the superposed margin of the outer and lining portions to pressure with the mulled stiffening blank between them the margins of all three plies are cemented or fused together in a single inturned flange. The heel pocket is then allowed to dry upon the last, whereupon the stiffener is transformed into a 50 stiff condition but now in such molded shape as to impart to the shoe permanently the lines of the last. At the completion of the drying operation, the shoe, including the heel pocket, may be safely removed from the last without danger of being misshapen or distorted.

55 It will be noted that by the steps explained the heel pocket is not only molded permanently into the final shape desired in the shoe but it is at the same time incorporated into the structure of the shoe. It is contemplated, however, that in some cases, it may be advantageous to assemble the heel pocket and mold or shape it upon a form which is the counterpart of the last, that is, the operation of shaping the heel pocket may

be carried out independently of the shoe and subsequently the molded heel pocket may be incorporated into the shoe. Such procedure is particularly useful in the manufacture of slippers, whereas it would not apply to the manufacture of 5 women's pumps or oxfords.

The invention has been discussed in its application to the manufacture of slippers for purposes of illustration only. It may be usefully applied in the manufacture of women's shoes in 10 general, both in sandals and in shoes where a seamless counter portion is desired.

15 The step of drying and transforming the stiffening blank from its mulled, pliable and adhesive condition to the stiff resilient condition required in the finished shoe may be carried out at room temperature or with the assistance of artificial heat. The latter is usually preferable both from the standpoint of economy of time and because a 20 higher rate of drying usually imparts a greater degree of stiffness to the stiffening material.

25 Having thus described my invention, what I claim as new and desire to secure by Letters Patent of the United States is:

30 1. A process of shoemaking which includes the steps of preparing, independently of the shoe, a lined heel pocket having a rolled upper edge with the line of juncture between the lining and outer portion located entirely within the heel pocket, inserting a stiffening piece which extends 35 upwardly above said line of juncture in the heel pocket, lasting the heel pocket with the stiffener piece therein to form an inturned heel seat flange, and then drying to stiffen the heel pocket in the shape of the last.

40 2. A process of shoemaking which includes the steps of preparing, independently of the shoe, a lined heel pocket having its upper and side edges shaped in a continuous curved contour with a rolled edge formed in the outer portion, locating a mulled stiffening piece in the heel pocket with its edge in substantial contact with the vertex of the rolled edge and above the line of juncture between the lining and outer portions, 45 working the free edges of the plies of the heel pocket over the last bottom, and drying to form a stiff integral flange of the fused material.

50 3. A molded heel pocket for a slipper, comprising an outer portion having an upper rolled edge, a lining portion having its line of juncture with the outer portion located below the rolled edge and in the inner surface of the heel pocket, and a stiffening piece which extends upwardly above said line of juncture and into contact with the rolled edge of the outer portion.

55 4. A process of shoemaking which includes the steps of stitching the outer and lining portions of a heel pocket along their upper edges, turning said portions to form a rolled upper edge and locate the stitch line in the inner face of the heel pocket, inserting a temporarily softened stiffening strip between said portions, and then molding the free margin of the portions into an integral in-turned flange.
